UNITED STATES PATENT OFFICE

CLARENCE E. JEFFERS, OF YORK, PENNSYLVANIA, ASSIGNOR, BY MESNE ASSIGNMENTS, TO HOUDAILLE-HERSHEY CORPORATION, A CORPORATION OF MICHIGAN

SELF-LUBRICATING FAN

Application filed April 21, 1927. Serial No. 185,415.

This invention relates primarily to the lubrication of rotatable machine elements, and more particularly to such elements as are adapted to rotate on stationary arbors. In addition to the novel lubricating features which are hereinafter described, my invention further embraces the application of these features to a novel fan construction.

It is an object of my invention to produce a simple and efficient means in conjunction with rotatable machine elements for rendering the latter self lubricating.

A further object relates to the adaptation of the principles of my invention to a fan and to the novel fan structure involved in this adaptation.

Other objects relate to certain features of construction and design conducive of simplicity and cheapness of manufacture.

An illustrative embodiment of my invention is found in the accompanying drawings wherein

Figure 1 is a longitudinal sectional view of a fan constructed in accordance with my invention,

Figures 2 and 3 are views in longitudinal section and end elevation respectively, of the hub or bushing portion of the fan as shown in Figure 1,

Figures 4 and 5 are views in end elevation and longitudinal section respectively of the oil collector element,

Figures 6 and 7 are views in end elevation and longitudinal section respectively of the oil collector cover plate,

Figures 8 and 9 are views in end elevation and longitudinal section respectively of the fan bushing thrust washer, and

Figures 10 and 11 are views in end elevation and longitudinal section respectively of a plate which co-acts with and forms a part of the oil collector shown in detail in Figures 4 and 5.

The fan with which my invention is associated as shown in the accompanying drawings comprises a sheet metal stamping 5 having radial projections 1 formed thereon, to which projections the several fan blades are adapted to be attached. The fan proper is adapted to be bolted or otherwise secured to

a radial flange formed on the rotatable hub 3. The entire assembly is adapted to rotate on a stationary arbor 2. As above indicated, the body of the fan is formed of sheet metal by a suitable stamping process, such body having a centrally arranged cupped portion from which the arms 1 extend radially for the reception of the fan blades.

Secured to the radial flange 6 of the bushing 3 is a cylindrical oil tight casing 4 which is somewhat longer than the bushing and which surrounds the shaft 2. Suitable packing is employed at the point where a shaft 2 passes through the casing 4. Suitable packing is also employed between the flange 6 of the hub and the co-acting flanges of the casing 4 and fan 1 respectively. The casing 4 is adapted to contain a lubricant, preferably an amount such as indicated by the dotted oil level line shown in Figure 1, and to this end the casing is provided with a filling plug 19 through which the lubricant may be introduced or withdrawn.

Secured to the end of shaft 2 and in abutting relation therewith and with the corresponding end of bushing 3 is a thrust washer 9. This washer is provided with radially extending openings which expose portions of the bearing surface between the sleeve 3 and the non-rotatable shaft. Outwardly of the thrust washer is mounted an oil collecting disk 10 having formed thereon radial vanes 16 which are adapted to register with the several radial openings in the thrust washer. The registration of the vanes with the openings in the thrust washer is assured by means of the stamped out lugs 12 on the plate 10 engaging in the radial slots. Outwardly of the oil collecting plate 10 and in concentric relation therewith is a cover plate member 11.

This member is in the form of a cup having a central aperture through which the securing bolt 15 passes to maintain the same together with the oil collecting plate and the thrust washer in concentric assembled relation. The overturned edge of the cup member 11 is adapted to project rearwardly of the shaft and cover the circumference of the oil collecting plate. The hub 3 is formed with a shoulder intermediate the flange 6 and the

end of the hub. Mounted on this shoulder is a plate 13 which co-acts with the vanes of the oil collector plate to form a plurality of closed radially extending passages. The plate 13 is maintained in assembled relation with the oil collector plate by means of the up-standing flanges 14 which are adapted to be positioned within the radial openings 20 of the collector plate. The flange 6 of hub member 3 is provided at a point adjacent the inner surface of the casing 4, with an aperture 8 which is adapted to pass lubricant from within the casing 4 to the oil collecting assembly on the end of shaft 2.

15 It will be understood that in operation the lubricant contained within the casing 4 will assume the form of an annular film on the inner surface of the cylinder by virtue of centrifugal force. Portions of this annular film of lubricant will be projected laterally through the openings 8 and into the oil collector where it will be conveyed radially inward by means of the several vanes 16. Due to the fact that the vanes 16 register with the 20 radial slots of the thrust washer 9, it is apparent, that the lubricant thus collected and carried inwardly will be fed to the bearing surface between the sleeve 3 and the shaft. In order to facilitate the starting of the flow 25 of oil between the co-acting bearing surfaces, I have provided an undercut recess 17 within the hub 3 which is adapted to collect and retain the initial lubricant charge. From this recess the lubricant will gradually work along 30 the entire length of the bearing surface until the point 21 is reached, at which point a large part of the lubricant will again be discharged through the openings in the sleeve back into the casing. In order to insure lubrication of the sleeve beyond these discharge 35 openings, I have provided a spiral groove on the inner surface of the sleeve beginning at the points where these openings are located, and extending to the end of the sleeve. The reason for locating the openings at the point 40 21 is to prevent the discharge of the entire body of lubricant directly against the packing through which the shaft 2 passes.

It should be apparent from the foregoing 45 description that my device embodies a means for maintaining a constant and substantially uniform flow of lubricant in a continuous circuit from the casing inwardly to the bearing surface of the shaft and back to the casing. An important feature of my invention is that the particular design employed permits of the use of sheet metal stampings for practically all of the parts. It is also noted that the elements added to the fan structure proper 50 for the purpose of lubricating the fan bearing are permanently held stationary and therefore are not subject to wear.

I do not intend by the foregoing description 55 to limit my invention to a fan construction, since it is apparent that the underlying

principles thereof may be applied to numerous other rotatable machine elements. In so far as the broader aspects of my invention are concerned, it is immaterial what be the nature of the machine element which is secured to the flange of the bearing hub. It is apparent that the flange 6 of the bearing hub might carry a conventional gear wheel, pulley, sprocket or in fact any rotatable element.

What I claim as my invention is:

1. In a device of the character described, the combination with a non-rotatable shaft, a thrust washer secured to said shaft, an elongated sleeve having a bearing on said shaft and having an end abutting said washer, a radial flange on said sleeve, a rotatable machine element secured to one face of said flange, a lubricant tight casing secured to the opposite face of said flange, said thrust washer having radial slots of sufficient depth to expose portions of the bearing surface between said sleeve and shaft, a disc secured to said shaft outwardly of and adjacent to said washer and having radial vanes and an aperture through said flange adjacent the inner surface of said casing, whereby, during rotation of said machine element, lubricant is discharged from said casing through the aperture and onto said vanes, and by said vanes directed inwardly to said bearing.

2. In a device of the character described, the combination with a non-rotatable spindle, of a sleeve journaled thereon, a lubricant containing casing secured for rotation with said sleeve, means within said casing for receiving and conducting lubricant therefrom inwardly to the bearing surfaces of said sleeve and spindle, said means comprising two spaced discs having radially disposed vanes extending therebetween, and being so located that said vanes terminate inwardly adjacent the aforementioned bearing surfaces and means for securing said lubricant conveying means in non-rotatable relation to said spindle.

3. In a device of the character described, the combination with a non-rotatable spindle, of a sleeve journaled thereon, a thrust washer secured to an end of said spindle and affording a thrust bearing surface for the adjacent end of said sleeve, a lubricant conducting means mounted on said end of the spindle, said washer having a slot affording communication between said lubricant conducting means and the bearing surfaces of said sleeve and spindle and also affording means of maintaining said lubricant conducting means in non-rotative relation with said spindle, a lubricant containing casing surrounding said spindle and sleeve and secured for rotation with the latter and adapted to discharge lubricant therefrom into said conducting means.

4. In a device of the character described, the combination with a non-rotatable spin-

dle, of a sleeve journaled thereon, a radial flange secured to said sleeve adjacent an end thereof, a casing structure secured to said flange and affording a closed chamber on either side thereof, one of said chambers adapted to contain a supply of lubricant and said flange having an aperture extending therethrough for placing said chambers in communication, means in said other chamber for receiving lubricant discharged through said aperture and conducting it inwardly to the bearing surfaces of said sleeve and spindle, said means comprising a washer secured to said spindle and abutting the adjacent end of said sleeve, said washer having radial slots of a depth to expose said bearing surfaces, a disc interlocked with said washer and having radial vanes formed on a face thereof, a second disc spaced from but interlocked with the first disc and coacting with the vanes thereof to form closed radial passages, and means for securing said discs to said spindle.

5. In a self-lubricating fan structure of the type embodying a fixed spindle, a sleeve having a bearing thereon, and a two compartment casing surrounding said spindle and sleeve and secured for rotation with the latter and wherein one compartment is adapted to contain a supply of lubricant and discharge the same centrifugally into the other compartment, the combination therewith of means disposed in said second compartment for receiving the lubricant discharged thereinto and conducting the same inwardly to the bearing surfaces of said sleeve and spindle, and comprising a pair of spaced interlocked discs having radially disposed vanes extending therebetween and terminating outwardly adjacent the point of discharge from said supply casing and inwardly adjacent the aforesaid bearing surfaces.

6. In a self-lubricating fan structure of the type embodying a spindle, a sleeve having a bearing thereon and a two compartment casing surrounding said spindle and sleeve and secured for rotation with the latter and wherein one compartment is adapted to contain a supply of lubricant and discharge the same centrifugally into the other compartment, the combination therewith of means disposed in said second compartment for receiving the lubricant discharged thereinto and conducting the same inwardly to the bearing surfaces of said sleeve and spindle and comprising a thrust washer abutting the adjacent ends of said sleeve and spindle and secured to the latter and having radial slots of a depth to expose said bearing surfaces, a disc interlocked with said washer and having radial vanes in radial alignment with said slots and a second disc spaced from and interlocked with the first mentioned disc an abutting the free edges of said vanes to form therewith closed radial passageways.

7. The structure set forth in claim 6, in combination with a third disc concentric with the two discs aforesaid and having an annular horizontally disposed flange overlying the latter and means for securing the several said discs and washer in concentric relation to said spindle.

8. In a device of the character described, the combination with a non-rotatable shaft, a thrust washer secured to said shaft, an elongated sleeve having a bearing on said shaft and having an end abutting said washer, a radial flange on said sleeve, a rotatable machine element secured to one face of said flange, a lubricant tight casing secured to the opposite face of said flange, said thrust washer having radial slots of sufficient depth to expose portions of the bearing surfaces between said sleeve and shaft, a sheet metal disk secured to said shaft outwardly of and adjacent to said washer, said disk having radial vanes struck therefrom, said vanes terminating inwardly adjacent said washer and an aperture through said flange adjacent the inner surface of said casing, whereby during rotation of said machine element lubricant is discharged from said casing through the aperture and onto said vanes and by said vanes directed inwardly to said bearing.

9. In a device of the character described, the combination with a non-rotatable spindle, of a sleeve journaled thereon, a radial flange secured to said sleeve adjacent an end thereof, a casing structure secured to said flange and affording a closed chamber on either side thereof, one of said chambers adapted to contain a supply of lubricant and said flange having an aperture extending therethrough for placing said chambers in communication, means in said other chamber for receiving lubricant discharged through said aperture and conducting it inwardly to the bearing surfaces of said sleeve and spindle, said means comprising a washer secured to said spindle and abutting the adjacent end of said sleeve, said washer having radial slots of a depth to expose said bearing surfaces, a sheet metal disk associated with said washer, said disk having a projection struck therefrom and adapted for engagement with one of said radial slots of the washer and also having a plurality of radial vanes struck therefrom and adapted to be held in a predetermined position with respect to the slots of said washer by said projection, and means for securing said disk and washer in assembled relation with said spindle.

10. In a device of the character described, the combination with a relatively fixed spindle and a fan assembly having rotatable bearing support thereon embodying two closed chambers and a passageway for placing them in communication, one of said chambers being adapted to serve as a lubri-

cant reservoir and the other being adapted to receive lubricant from said reservoir through said passageway and means disposed in said other chamber for collecting the lubricant so received therein and conveying the same to the bearing surface of said spindle, said means comprising a disc having vanes, a second disc abutting the free edges of said vanes and a third disc having a circumferential flange surrounding the peripheral portions of said vanes whereby to form substantially closed lubricant pockets between the vanes, one of said discs being so formed as to provide openings between the same and said circumferential flange whereby lubricant may be introduced into said pockets from the said passage, said pockets terminating inwardly adjacent to and having communication with the said spindle bearing surface for supplying lubricant thereto.

11. In a device of the character described, the combination with a relatively fixed spindle and a fan assembly having rotatable bearing support thereon embodying two closed chambers and a passageway for placing them in communication, one of said chambers being adapted to receive lubricant from said reservoir through said passageway and means disposed in said other chamber for collecting the lubricant so received therein and conveying the same to the bearing surface of said spindle, a disc having vanes and a second disc arranged adjacent thereto and cooperating therewith to form a lateral wall for said vanes, thus forming lubricant pockets between the successive vanes, means for conducting lubricant from said pockets to the bearing surface of said spindle and means for securing said discs in non-rotatable relation with said spindle.

12. In a fan of the type embracing a relatively fixed spindle and a fan assembly having rotatable bearing support thereon and embodying two closed chambers and a passageway for placing them in communication and wherein one of said chambers is adapted to serve as a lubricant reservoir and the other is adapted to receive lubricant from such reservoir through said passageway, the combination therewith of means disposed in said other chamber for collecting the lubricant so received therein and conveying the same to the bearing surface of said spindle, said means comprising a disc having vanes and a second disc adjacent to and abutting said vanes and having a circumferential flange surrounding the peripheral portions of said vanes whereby to form substantially closed lubricant pockets between the vanes, such pockets terminating inwardly adjacent to and having communication with the said spindle bearing surface for supplying lubricant thereto.

13. In a fan of the type embracing a relatively fixed spindle and a fan assembly having rotatable bearing support thereon and embodying two closed chambers and a passageway for placing them in communication and wherein one of said chambers is adapted to serve as a lubricant reservoir and the other is adapted to receive lubricant from such reservoir through said passageway, the combination therewith of means disposed in said other

chamber for collecting the lubricant so received therein and conveying the same to the bearing surface of said spindle, said means comprising a disc having vanes, a second disc abutting the free edges of said vanes and a third disc having a circumferential flange surrounding the peripheral portions of said vanes whereby to form substantially closed lubricant pockets between the vanes, one of said discs being so formed as to provide openings between the same and said circumferential flange whereby lubricant may be introduced into said pockets from the said passage, said pockets terminating inwardly adjacent to and having communication with the said spindle bearing surface for supplying lubricant thereto.

14. In a fan of the type embracing a relatively fixed spindle and a fan assembly having rotatable bearing support thereon and embodying two closed chambers and a passageway for placing them in communication and wherein one of said chambers is adapted to serve as a lubricant reservoir and the other is adapted to receive lubricant from such reservoir through said passageway, the combination therewith of means disposed in said other chamber for collecting the lubricant so received therein and conveying the same to the bearing surface of said spindle, said means comprising a washer secured to said spindle and serving as an end thrust member for said fan assembly, said washer having radial slots which expose the bearing surface of said spindle, a disc secured to said spindle and having interlocking engagement with said washer for maintaining the disc and washer in a predetermined relative position, said disc being formed with a plurality of substantially radially disposed vanes, a second disc secured to said spindle in abutting relation to the free edges of said vanes whereby to form pockets between them and said discs being so arranged that said pockets communicate with the slots of said washer, whereby lubricant is fed to the bearing surface of said spindle.

15. In a fan of the type embracing a relatively fixed spindle and a fan assembly having rotatable bearing support thereon and embodying two closed chambers and a passageway for placing them in communication and wherein one of said chambers is adapted to serve as a lubricant reservoir and the other is adapted to receive lubricant from said reservoir through said passageway, the combination therewith of means disposed in said other chamber for collecting the lubricant so received therein and conveying the same to the bearing surface of said spindle, said means comprising a washer secured to said spindle and serving as an end thrust member for said fan assembly, said washer having radial slots which expose the bearing surface of said spindle, a disc secured to said spindle and

having interlocking engagement with said washer for maintaining the disc and washer in a predetermined relative position, said disc being formed with a plurality of substantially radially disposed vanes, a second disc secured to said spindle in abutting relation to the free edges of said vanes whereby to form pockets between them, and a third disc having a circumferential flange surrounding the peripheral extremities of said vanes and one of said discs being formed to provide openings between the same and said flange whereby lubricant may be introduced into said pockets, and said discs being so arranged that said pockets communicate with the slots of said washer, whereby lubricant is fed to the bearing surface of said spindle.

In testimony whereof I affix my signature.
CLARENCE E. JEFFERS.
